US0D1034278S

(12) **United States Design Patent** (10) **Patent No.:** **US D1,034,278 S**
(45) **Date of Patent:** **** Jul. 9, 2024**

(54) **WATCH STRAP**

(71) Applicant: **Quan Zheng**, Shenzhen (CN)

(72) Inventor: **Quan Zheng**, Shenzhen (CN)

(**) Term: **15 Years**

(21) Appl. No.: **29/924,449**

(22) Filed: **Jan. 18, 2024**

(30) **Foreign Application Priority Data**

Dec. 25, 2023 (CN) 202330850791.7

(51) **LOC (14) Cl.** **11-01**

(52) **U.S. Cl.**

USPC **D11/3**

(58) **Field of Classification Search**

USPC D11/1-5; D10/32

CPC A44C 5/00

See application file for complete search history.

(57) **CLAIM**

The ornamental design for a watch strap, as shown and described.

DESCRIPTION

FIG. 1 is a front, right and bottom perspective view of a watch strap, showing my new design;

FIG. 2 is a rear, left and top perspective view thereof;

FIG. 3 is a perspective view of the design in a state of use;

FIG. 4 is a perspective view of the design in a state of use;

FIG. 5 is a front view thereof;

FIG. 6 is a rear view thereof;

FIG. 7 is a left side view thereof;

FIG. 8 is a right side view thereof;

FIG. 9 is a top plan view thereof;

FIG. 10 is a bottom plan view thereof;

FIG. 11 is an enlarged view of portion of FIG. 1 thereof; and,

FIG. 12 is an enlarged view of portion of FIG. 2 thereof.

The broken lines shown in the drawings illustrate portions of the watch strap that form no part of the claimed design. The broken lines in FIGS. 3 and 4 illustrating a watch face is for the purpose of showing environmental structure and form no part of the claimed design.

1 Claim, 12 Drawing Sheets
